Primary Examiner — Eliza Z Harvey*Assistant Examiner* — Landon Thomas Cassell(74) *Attorney, Agent, or Firm* — Husch Blackwell(57) **CLAIM**

The ornamental design for a charging cable as shown and described.

DESCRIPTION

FIG. 1 is a perspective view of a charging cable.

FIG. 2 is a front elevational view of the charging cable depicted in FIG. 1.

FIG. 3 is a rear elevational view of the charging cable depicted in FIG. 1.

FIG. 4 is a right side elevational view of the charging cable depicted in FIG. 1.

FIG. 5 is a left side elevational view of the charging cable depicted in FIG. 1.

FIG. 6 is a top plan view of the charging cable depicted in FIG. 1; and,

FIG. 7 is a bottom plan view of the charging cable depicted in FIG. 1.

The broken lines in the drawings illustrate portions of the charging cable that form no part of the claimed design. The pair of unevenly spaced dot-dash broken lines depict a symbolic break in drawings, the dot-dash line form no part of the claimed design, any appearance of the article between the broken lines forms no part of the claimed design.
